United States Patent Office

Des. 227,210
Patented June 12, 1973

227,210

CHAIR

Thomas Winrow, 530 S. Sleigh,
Naperville, Ill. 60540

Filed Apr. 22, 1971, Ser. No. 136,653

Term of patent 14 years

Int. Cl. D6—02

U.S. Cl. D6—73

The figure is a perspective view of a chair illustrating my new design.

The back of the chair is conventionally plain while the side not shown is substantially identical to the side shown.

I claim:

The ornamental design for a chair, as shown and described.
